UNITED STATES PATENT OFFICE.

OLOF H. JACOBSON, OF KANSAS CITY, MISSOURI.

ADJUSTABLE TOOL-HANDLE.

1,119,827.

Specification of Letters Patent.

Patented Dec. 8, 1914.

Application filed March 7, 1914. Serial No. 823,104.

To all whom it may concern:

Be it known that I, OLOF H. JACOBSON, a citizen of Sweden, residing at Kansas City, in the county of Jackson and State 5 of Missouri, have invented certain new and useful Improvements in Adjustable Tool-Handles, of which the following is a specification.

My invention relates to improvements in 10 adjustable tool handles, and my object is to provide a device of this character for holding files, chisels, and other tools having a tang to receive my handle.

In order that the invention may be fully 15 understood, reference will now be made to the accompanying drawing, in which:

Figure 1 is a broken side elevation of a file and my handle in position thereon. Fig. 2 is a central vertical section on line 20 II-II of Fig. 1. Fig. 3 is a cross section on line III-III of Fig. 2. Fig. 4 is a cross section on line IV-IV of Fig. 2. Fig. 5 is a detail of one of the chuck members employed in carrying out the invention.

25 A, designates a file of ordinary construction provided at one end with the usual tang B.

1 designates my handle which is of hollow construction to receive the adjustable 30 means for firmly gripping files of different sizes. Handle 1 is reinforced at its forward end with a ferrule 2, provided at one side with an internal resilient detent 3, one end of which projects forwardly through 35 said ferrule and is bent at right angles to constitute a finger piece 4, whereby it may be retracted against the side of the ferrule, as will hereinafter appear. Detent 3 contacts with a ratchet-wheel 5, rotatably 40 mounted in the forward end of the ferrule 2 and having a slot 6 for the passage of the tang B. The teeth 3^a of the ratchet-wheel 5, overlap the inner surface of a marginal flange 2^a of the ferrule 2, and thus hold 45 said ratchet-wheel in the ferrule.

7 designates a chuck bearing at one end against the ratchet-wheel 5 and at its opposite end against the closed rear end 8 of the handle 1. Chuck 7 consists of a pair 50 of members 9 having tapered channels 10, to receive the tang B.

11 designates a resilient clamping member, preferably, in the form of a coil spring embracing the chuck members 9. The 55 clamping member 11, is secured at one end to one of said chuck members and at its

opposite end to a member 12 countersunk in one side of the handle 1.

In practice, the tang B of the file, or other tool, is inserted in the channel of the 60 chuck members 9 as far as possible and then rotated in a direction to unwind the spring 11, so that the tang B may be pushed farther into the channel 10. After the tang B has been inserted practically its entire 65 length, the file is rotated in the opposite direction to wind the spring 11, so that it will cause the chuck-members 9 to firmly grip the tang and reliably secure it in the handle. While the file is being rotated to 70 unwind or wind the spring 11, the detent 3 is held out of engagement with the ratchet-wheel 5, but after the spring has been wound as above described, it is secured against accidental unwinding by releasing the detent 3 and permitting it to 75 enter one of the peripheral notches 13 of said ratchet-wheel 5.

By employing a resilient clamping member to control the chuck members 9, the 80 latter are permitted to accommodate themselves to tangs of different sizes and shapes and thus firmly grip said tangs, so that the tools will be firmly held from wabbling or moving independently of the handle when 85 the spring is wound as above described.

Having thus described my invention, what I claim and desire to secure by Letters Patent, is:

1. A device of the character described, 90 consisting of a handle, a plural piece tool holder arranged in said handle, a helical spring embracing said tool holder and adapted to cause the same to firmly grip a tool when the latter is rotated to wind 95 the spring, and means to secure said spring in wound condition.

2. A device of the character described, 100 consisting of a handle, a plural piece tool holder arranged in said handle, and a coil spring embracing said tool holder and secured at one end thereto and at its opposite end to the handle, said spring being adapted to cause the tool holder to firmly grip a tool when the latter is rotated to wind 105 the spring.

3. A device of the character described, 110 consisting of a handle, a plural piece tool holder arranged in said handle, a coiled clamping member embracing said tool holder to cause the same to firmly grip a tool when the latter is rotated to wind said

clamping member, a ratchet wheel to prevent accidental unwinding of said clamping member, and means to secure said ratchet wheel from accidental rotation.

4. A device of the character described, consisting of a handle, a two-piece chuck within said handle, a coil spring embracing said chuck to cause it to firmly grip a tool when the latter is rotated to wind said spring, a ratchet wheel having a slot for the passage of the tool, said ratchet wheel being adapted to secure the spring from accidental unwinding, and a detent to secure said ratchet wheel from accidental rotation.

5. A device of the character described, consisting of a handle having a recess there-

in, a plural piece chuck in said handle, a coil spring embracing said chuck to cause it to firmly grip a tool when the same is rotated to wind the spring, a ratchet wheel bearing against the opposite end of the chuck and provided with a slot to admit one end of a tool to said chuck, a ferrule secured to one end of the handle andlapping the ratchet wheel to hold the same in position, and a detent coating with said ratchet wheel.

In testimony whereof I affix my signature, in the presence of two witnesses.

OLOF H. JACOBSON.
